UNITED STATES PATENT OFFICE

2,310,215

CONTINUOUS RETORT

McGarvey Cline, Jacksonville, Fla.

Application May 3, 1939, Serial No. 271,595

10 Claims. (Cl. 202—105)

This invention relates to continuous retorts for subjecting materials to the action of heat, and more particularly to retorts in which the heating medium does not come in contact with the materials being processed and where the products resulting from the action of heat on the materials may be readily recovered.

While the invention is primarily adapted for processing solid materials in finely divided form, it may also be applied to the treatment of certain concentrated solutions or suspensions. Among the substances which may be treated, are wood in the form of small chips, sawdust or powder; concentrated liquors produced in the paper pulp industry; agricultural waste products such as straw, corn stalks, tobacco stems, wheat and oat hulls, etc., when such materials are finely divided or shredded; and nut hulls, seed pits, shredded bone, etc.

In its broadest aspects, the invention is applicable to the simple drying of materials such as those above mentioned, but it is intended more particularly for the destructive distillation of such materials, whereby they are completely carbonized, and, at the same time, the vapors and gaseous products resulting from the distillation may be recovered. The invention has special utility when used for the destructive distillation of resinous wood, such as that of the southern pine.

Many efforts have been made to successfully distill the large amount of waste pine wood available in this country both in the form of stumps, limbs, etc., left in the operation of saw mills, or in the form of finely divided chips produced in the wood naval stores industry and left as a residue after the oleo-resinous materials have been extracted by means of solvents. The destructive distillation of such material, however, has heretofore presented difficult practical problems, owing to the peculiar nature of the material, and it is the general object of the present invention to devise effective means for carbonizing resinous woods, particularly the spent chips above referred to, with the coincident recovery of valuable products such as phenols and other distillates.

The apparatus of the present invention may be considered as a further development of and improvement on that disclosed in my prior Patent No. 1,763,758, issued June 17, 1930, and while the present invention relates to apparatus of the same general type as that of said patent, it possesses marked advantages thereover.

Among the specific objects of the present invention are to provide improved means for supporting and rotating the retort; and improved means for supporting the top or superstructure thereof; to devise an improved heating element having means for causing the hot gases to flow

therethrough more effectively; to provide improved conveyor elements for handling the material more effectively; to provide improved means for driving the feeding and discharging mechanism; to provide improved feeding mechanism which will serve to deliver measured quantities of material into the retort in such a manner as to prevent packing and jamming, and will, at the same time, prevent the escape of gaseous products; to provide means for separating the dust and fine particles of solid matter from the vapor and gaseous products rising from the material being treated; to provide means for positively ejecting from the conveyors any material which, due to coking, or for other reasons, adheres thereto and fails to be discharged by gravity; and to devise an improved arrangement for circulating hot gases through the heating elements in such manner that the temperature thereof may be accurately and definitely controlled as desired.

With the above and other objects in view, the invention consists in the construction and arrangement of parts hereinafter described and claimed, and illustrated in the accompanying drawings forming part of this specification, and in which:

Fig. 1 is a side elevation of my improved retort complete, parts being broken away and parts being shown in section;

Fig. 2 is a plan view on an enlarged scale of the top of the apparatus, parts being omitted for the sake of clearness, and parts being broken away;

Fig. 3 is a horizontal section substantially on the line 3—3 of Fig. 1, but showing parts not appearing in Fig. 1;

Fig. 4 is a fragmentary, vertical, central section on an enlarged scale through the lower part of the apparatus shown in Fig. 1;

Fig. 5 is a similar section on the same scale through the upper part of the apparatus;

Fig. 6 is a plan view of one of the improved heating elements;

Fig. 7 is a transverse section thereof substantially on the line 7—7 of Fig. 6, looking in the direction of the arrows;

Fig. 8 is a plan view of the supporting ring on which the lowermost heating element rests;

Fig. 9 is a transverse section on the line 9—9 of Fig. 8, looking in the direction of the arrows;

Fig. 10 is a fragmentary side elevation on an enlarged scale, showing two superposed heating elements with one of the conveyor elements between them, and illustrating my improved means for ejecting caked material from the conveyor;

Fig. 11 is a plan view of the topmost conveyor element and associated parts;

Figs. 12 and 12^a together constitute a transverse section substantially on the line 12—12 of

Fig. 11, looking in the direction of the arrows, the superposed parts being shown as separated;

Fig. 13 is a fragmentary plan view of one of the series of intermediate conveyor elements which I employ;

Fig. 14 is a central transverse section therethrough;

Fig. 15 is a vertical longitudinal section on an enlarged scale showing the details of the improved feed mechanism illustrated in general in Fig. 1;

Fig. 16 is a vertical transverse section substantially on the line 16-16 of Fig. 15, looking in the direction of the arrows;

Fig. 17 is a fragmentary vertical section through the lower part of the apparatus substantially on the line 17-17 of Fig. 3;

Fig. 18 is a vertical transverse section substantially on the line 18-18 of Fig. 3, looking in the direction of the arrows;

Fig. 19 is a fragmentary sectional view on an enlarged scale substantially on the line 19-19 of Fig. 18, showing details of my improved temperature controlling apparatus; and

Fig. 20 is a horizontal section substantially on the line 20-20 of Fig. 4, looking in the direction of the arrows.

Referring to the drawings in detail, and more particularly first to Fig. 1, my improved apparatus comprises a supporting base A and associated parts, a rotatable vertical cylindrical shell B, constituting the body of the retort, and a stationary top or superstructure C.

Referring now more particularly to Figs. 1 and 4, the base comprises a cylinder 1, preferably made of metal and resting upon a suitable foundation 2. On top of the cylinder 1 is supported a base plate 3, extending entirely across the apparatus and having an opening therein concentric with the cylinder 1.

Supported upon the base plate 3 just above the cylinder 1 is a ring shaped rail or track 4, on which the rotary cylindrical shell revolves, as hereinafter described.

This shell comprises a lower section 6, to which is secured a horizontal annular flange 5, from which depend an intermediate vertical cylindrical web 7 and an outer concentric web 8 spaced apart as shown. Also secured to the cylindrical section 6 is an angle flange 9, adapted to support a similar flange, secured to the lower end of the main cylindrical shell of the retort.

To the outer wall 8 is secured an angle flange 10, to the under side of which is secured, by bolts 11, an annular ring gear 12 having teeth on its outer periphery.

Mounted beneath the ring gear 12 and secured thereto as by means of some of the bolts 11 are a plurality of rollers 13 adapted to bear against the outer vertical surface of the ring rail 4.

Secured to the upper surface of the ring gear 12 are a plurality of bearing housings or journal boxes 14, containing bearings in which are journalled the spindles of supporting wheels 15, which rest and ride upon the upper surface of the ring rail 4. Thus the weight of the rotary shell is carried by the wheels 15, and it is centered and held against lateral displacement by the rollers 13, bearing against the outer face of the ring rail.

Secured to the base plate 3 at a point just inside of and spaced from the depending web 7 is an upstanding cylindrical web 16, and also secured to the base plate 3 just outside of and spaced from the web 7 is a similar upstanding

cylindrical web 17. It will thus be seen that the cylindrical webs or rings 16 and 17 form, with the base plate 3, an annular trough into which the depending web or ring 7 extends. This trough is partially filled with some suitable liquid (not shown) into which the web 7 dips so as to form a gas tight seal around the bottom of the retort.

The main body B of the retort comprises a cylindrical shell 19, to the lower edge of which is secured an angle ring 18, mating with and attached to the angle ring 9.

Resting on the base plate 3 is a supporting ring 20, shown as of frusto-conical form, having a horizontal base flange 21 terminating in a short vertical flange 22, which fits snugly within the opening in the base plate 3. This supporting ring is best shown in Figs. 8 and 9, and is adapted to be secured to the base plate 3 by means of bolts passing through holes 21a, which, as shown, are preferably spaced 22½° apart. This is done so that the supporting ring may be angularly adjusted with respect to the base plate and set in any desired one of sixteen different positions.

At the upper edge of the ring 20 is a groove 23 preferably having tapered sides, as shown, for the purpose of making a tight joint with the lowermost heating element, as hereinafter described.

The ring 20 is provided with an inwardly projecting lug 24, with a series of strengthening webs 25, and with a series of eight pairs of radially extending lugs 26, the purpose of which will be hereinafter explained.

As in my former patent, above referred to, the retort comprises a vertical series or stack of hollow annular heating elements. In the present case, however, these heating elements designated in their entirety by the reference numeral 27, are of improved construction, the details of which are best shown in Figs. 6 and 7.

Each annular heating element has, at its lower edge, a conical flange adapted to fit into the groove 23 of the supporting ring 20, or into a similar groove 32 formed at the upper edge of each heating element, as the case may be, so that when the heating elements are assembled or stacked up in superposed relation, as shown in Figs. 4 and 5, their meeting edges are sealed and their interiors are in continuus communication.

Referring again to Figs. 6 and 7, each improved heating element comprises spaced bottom and top walls 29 and 30, reinforced by radial connecting webs 31, and are preferably formed by casting. It will be understood that these webs 31 are preferably spaced similar to the webs 25, shown in Fig. 9, each, in the embodiment shown, being 22½° apart, so that when the superposed elements are assembled in the form of a stack, these strengthening webs will be in vertical alignment throughout the stack. Supported by the webs 31 and extending between the upper and lower walls 29 and 30 in an annular baffle 33, of somewhat dished form, as shown. Around the inner periphery of this baffle is a thickened vertically disposed rib or flange 34, extending both above and below the same, and projecting horizontally inward from this thickened rib is a narrow, annular, horizontal flange 35. The inner portion of the baffle 33 is preferably provided with a plurality of radially extending slots 36 for permitting expansion and contraction of the baffle under changing temperature conditions.

As in my prior patent, each heating element is provided with a notch or sector-shaped opening 38 of approximately 22½° in extent, the hollow

interior of the heating element being closed by radial walls 39 at either side of this notch.

Each heating element is provided, at its lower edge, adjacent the said notch, with a downwardly projecting lug 23', adapted to engage the lug 24 on the base ring 20 (Fig. 8) or to engage a similar lug 24', (Fig. 6) formed at the upper edge of each heating element, so as to angularly position one with respect to the other.

Each heating element 27 is further provided adjacent its upper edge with a series of eight pairs of inwardly projecting radial lugs 37, and adjacent its lower edge with a similar series of eight pairs of inwardly projecting radial lugs 37', the lugs of one series being staggered with respect to those of the other, so that in plan view, as shown in Fig. 6, there is a pair of lugs 22½° around the inner periphery of the heating element.

From the foregoing, it will be obvious that in assembling the heating elements on the supporting ring 20 and on each other to form a stack, as shown in Figs. 4 and 5, each heating element may be so positioned that the notch 38 therein is angularly displaced 22½° from the notch in the heating element next below, whereby the notches are arranged in a broken spiral around the stack, and are not in vertical alignment, but offset from each other, as shown in Fig. 10. It will further be understood that, the supporting ring 20 having once been bolted in position with the lug 24 at the desired point, this lug will determine, by means of the key lug 28' on the heating elements, the angular position of the lowest heating element and the location of the notch 38 therein. The remaining heating elements can then be progressively angularly displaced so that the notches therein define a spiral as above mentioned, the notch in the lowermost heating element being disposed at the left hand side of the apparatus adjacent the discharge mechanism, as shown in Fig. 4, and the notch in the uppermost heating element being disposed almost in the same vertical line but displaced therefrom a distance of 22½° in a counter-clockwise direction, as illustrated in dotted lines in Fig. 2. When the series of heating elements have been assembled on the supporting ring 20, and on each other in superposed relation, and in the desired relative angular positions, they are secured together by means of bolts 41 passing through vertically aligned pairs of lugs 37' and 26 or 37, as the case may be (see Fig. 4). No attempt has been made to illustrate all of these lugs in Figs. 4 and 5, however, only one or two pairs being illustrated for the sake of clearness.

On the under side of each heating element adjacent the opening or notch therein is formed a series of concentric depending ribs 40 having bevelled or inclined lower surfaces 40a, as shown in Fig. 10. The purpose of these ribs will be herein-after explained.

As best shown in Figs. 4 and 5, the space between the inner peripheries of adjacent baffles 33 is closed by means of short cylindrical sections or walls 42. The edges of these sections fit within the annular shoulders 34 formed on the baffles and engage and are separated by the radial flanges 35.

It will thus be seen that the cylindrical sections 42 provide a continuous, central, vertical flue or conduit extending from the top to the bottom of the stack of heating elements.

It will further be observed that the cylindrical walls 42 are spaced inwardly from the meeting

edges of the heating elements 27, thus providing an annular opening between the interiors of adjacent elements.

Depending from the lower side of the base plate 3 and concentric with the above mentioned conduit formed by the cylindrical sections 42, is a cylindrical casing 43, having a bottom plate 44 provided with a concentric opening. Extending upward from this opening is a pipe 45 (Fig. 4). Beneath this opening and the lower end of pipe 45 is a radial duct 46, the purpose of which will be hereinafter described.

The inside of the cylinder 43 and the outside of the pipe 45 are preferably covered with a layer of heat resistant material 47, and this is shown as continued up through the supporting ring 20 by means of an additional section 48, on the top of which rests an annular ring 49, snugly fitting within the lowermost cylindrical section 42. It will thus be seen that the pipe 45 and wall 48 forms a continuation of the vertical axial conduit comprising the sections 42, and that this conduit communicates at its lower end with the radial duct 46.

Supported on and forming a tight connection with the uppermost heating element 27 is a top plate 50 having a central opening 51 therein (see Fig. 5) above which opening is secured a cylinder 52 having at its upper end a detachable cover 30 plate 53.

Tapping the side of the cylinder 43 (see Fig. 4) is a radial conduit 54, connected outside the base 1 with an enlarged section 55, both preferably lined with heat resisting material, as shown. The enlarged section 55 is connected at its outer end with a furnace 56, or other source of heat, the hot gases from the furnace preferably passing into the conduit 54, 55 through a delivery nozzle 57 spaced from the walls of the section 55, as shown.

The furnace conventionally indicated at 56 is preferably of the gas or oil burning type, having at its outer end a suitable fuel inlet 56a and air inlet means 56b (Fig. 3), whereby hot gases from the furnace are delivered through the nozzle 57 into the conduit 54. Any other suitable source of hot gases may, of course, be employed.

Tapping the furnace conduit 55 radially at a point adjacent the nozzle 57 is a pipe 58 (see Figs. 5, 4 and 18), this pipe being connected with a T 59 from the upper side of which extends a discharge flue or stack 60. The opposite end of the T 59 is connected with the discharge side of an air pump, shown as a centrifugal fan 61. A pipe 55 or flue 62 extends from the intake of the fan 61 to the bottom of the retort, where it connects with a short inclined section 46', communicating at its other end with the radial duct 46 (see Fig. 17).

In the T 59, I provide adjustable means for deflecting any desired portion of the gases delivered from the fan 61 into the outlet or discharge stack 60. As illustrated in Figs. 18 and 19, this deflecting means may consist of a damper 63 secured at 64 to a cross shaft journalled in the walls of the T, to the outer end of which shaft is attached an operating lever 65, through which passes a clamping bolt having an enlarged head 66, which works freely in an arcuate guide or slotted quadrant 68, the outer end of the bolt being threaded and fitted with a clamping nut 67. It is obvious that by loosening this nut, the lever 65, and with it the damper 63, may be swung to any desired angular position and then clamped in such position by tightening the nut.

70
75

Supported by and movable over the flat upper surface 30 of each heating element is an annular conveyor element of improved construction. As clearly shown in Figs. 13 and 14, this conveyor element comprises an inner ring 69; an outer angle ring 70, and a series of spaced radial bars 71 rigidly connecting said rings and forming therewith an annular series of cells closed on all four sides. These conveyor elements are adapted to be rotated by the cylindrical shell 19 through the medium of short drag chains 72 attached at one end to the ring 70 and at the other end to the shell. The preferable point of attachment of these chains is to the inner wall of flanged hand holes or openings 73, as shown in Figs. 4 and 5, provided with cover plates 74.

At the bottom of the retort adjacent and surrounding the supporting ring 20 is a special conveyor element comprising inner and outer rings 69' and 70' connected by radial bars 71', these bars being considerably deeper than the bars 71 of the standard conveyor elements and arranged with their lower edges just above the base plate 3. This special conveyor element fits snugly within the cylindrical section 6, at the bottom of the retort, and is supported on lugs 6a secured to the inner surface thereof. (See Fig. 4.)

On the topmost heating element is mounted another special conveyor element comprising an outer angle ring 70a, inverted as compared with the rings 70, and an inner angle ring 69a (see Figs. 5 and 12). This inner angle ring 69a is disposed with its upper horizontal leg overhanging the outer edge of the plate 59, as shown. Extending up from this horizontal leg is a lug 69b (Fig. 12), the purpose of which will hereinafter appear.

Coming now to the superstructure of the apparatus and referring more particularly to Figs. 2 and 5, I provide a top plate 75, shown as substantially square, and support this plate at its opposite sides upon longitudinal beams 76, which beams may conveniently constitute part of the framework of the building or shed in which the apparatus is housed. The longitudinal beams 76 rest upon and are connected by suitably spaced cross beams 77, as shown.

Depending from the lower side of the plate 75 is a cylindrical web or skirt 78 of slightly smaller diameter than the main cylindrical shell 19, and fitting within the same. To the upper end of the shell 19 is secured an annular trough 85, 86, and into this trough depends a second annular web or skirt 84, supported by the top plate 75, concentric with and spaced from the skirt 78. The trough 85 is adapted to contain a suitable liquid into which the skirt 84 dips, thus forming a fluid tight seal at the upper end of the rotating shell 19, between such shell and the stationary superstructure associated with the top plate 75. It will be here observed that there is no connection whatever between this superstructure and other parts of the retort, the superstructure being supported entirely by the beams or framing 76, 77, and the cylindrical shell 19 freely rotating beneath the same and out of contact therewith.

The top plate 75 has a central opening, from the inner edge of which depends a circular shell 79, concentric with the skirt 78 but spaced inwardly therefrom. The top plate 75 has an opening 75a extending between the elements 78 and 79, as shown in Fig. 5, and at both the front and rear of this opening, as viewed in Fig. 5, are vertical plates 80, bridging the space between

the elements 78 and 79, and forming therewith a closed chute, immediately below the opening 75a. Above this opening is a housing 81, into which the material to be treated is fed, as hereinafter described. The top of the housing 81 may be formed with a hand hole provided with a removable cover 81a.

Extending upwardly from the top plate 75 and registering with the central opening therein and forming a continuation of the circular wall 79, is a cylinder 82 provided with a cover plate 83.

To the bottom of the circular wall 79 is secured a horizontally disposed annular plate 87. (Figs. 2 and 5.) At one point in its circumference, as shown at the right hand side of Fig. 5, the wall 79 is provided with an opening 88, which merges at its lower end with a similar opening or notch 83a, formed in the plate 87 (Fig. 2).

Depending from the plate 87 is a curved diagonally extending scraper blade 89, the purpose of which will be hereinafter described.

Referring to Figs. 5, 11 and 12a, I provide a rotary member comprising an annular plate 90, having a depending peripheral flange 91, to the upper side of which plate is secured a vertical cylinder 92 having an internal flange 93 at the upper end thereof, such cylinder being of substantially less diameter than the plate 90. The inner edge of the annular plate 90 makes free sliding contact with the stationary cylinder 52.

When assembled, the lower edge of the flange 91 of the plate 90 rests upon and is supported by the upper horizontal leg of the angle ring 69a, and inside of the flange 91 is formed a lug 90a (Fig. 12a), which is adapted to engage the lug 69b (Fig. 12) so that the plate 90 and associated parts are caused to rotate with the conveyor element comprising the angle ring 69a. The plate 90 is centered and held against substantial lateral displacement by means of the cylinder 52.

The rotary cylinder 92 is of such size as to make a free sliding fit within the annular plate 87.

It will now be apparent that the elements 79, 87 and 92 together form an annular trough, the bottom and outer walls of which are stationary and the inner wall of which rotates.

Rigidly secured to the flange 93 at the top of the cylinder 92 is a pair of scrapers, each comprising a bracket 94 with blades 94a and 94b extending upwardly and downwardly therefrom. (Figs. 11 and 12a.) Strengthening ribs 95 preferably connect the blades with the bracket 94.

By reference to Fig. 5, it will now be seen that the edges 94' of the blades 94a travel in close proximity to the inner surface of the cylindrical chamber 82 and that the lower edges 94'' of the blades 94b work in close proximity to the annular plate 87 constituting the bottom of the trough, above referred to. When, therefore, the scrapers revolve, the blades scrape from the inner walls of the cylindrical chamber any solid matter which has been deposited thereon. This solid matter falls by gravity into the trough above described, and is moved along the bottom 87 thereof by means of the scraper blades and discharged downwardly through the opening 88a therein (Fig. 2). The discharged material falls upon the annular plate 90 (Fig. 5) from which it is swept outwardly by the scraper 89 and is deposited into the upper conveyor element comprising the rings 69a and 70a.

Extending radially out from the cylindrical chamber 82 is a discharge pipe 96 for the gases

and vapors resulting from the heat treatment of the material. This is connected at its outer end with the top of a suitable condenser 91, which is provided at its lower end with an outlet 97^a for discharging the non-condensable gases, which gases may be conducted to and burnt in the furnace 56. The condensed liquids pass through the pipe 98 into the well 98^a from which they overflow through the spout 99 into a suitable pipe or receptacle 99^a.

Feeding mechanism

The improved means which I have devised for feeding the finely divided material into the retort will now be described, special reference being had to Figs. 2, 5, 15 and 16.

It has been found that when attempting to feed finely divided material from a hopper, as for example by means of a discharge screw or a plunger, trouble is often experienced by reason of packing and arching of the material in the hopper. It has also been found that in feeding such materials by means of a piston and cylinder communicating directly with a hopper, the material is likely to become jammed or packed in the cylinder, with resultant strain or damage to the apparatus.

In designing my improved mechanism, I have succeeded in obviating both of the foregoing difficulties, first, by avoiding the use of a hopper containing a fixed mass of material, and second, by delivering predetermined quantities of material into the discharge cylinder.

My improved apparatus comprises a vertically disposed housing or chute having an opening 100 at its upper end, into which the material to be treated is preferably fed continuously. At the lower end of the chute or housing is a discharge opening formed by the walls 100^b and 100^c, the chute itself and associated mechanism being supported on a pair of spaced beams 76^a supported on the cross beams 77.

Mounted within and projecting from the chute or housing above described is a horizontal trough 101 of uniform width throughout, such trough being supported for free reciprocating movement on two pairs of rollers 102, one pair mounted on a shaft extending between the side walls 100' of the chute, and the other pair on a similar shaft extending between a pair of guide plates 107, referred to below. The trough 101 passes through an opening in the wall of the chute provided with a flange 100^a, and adjacent this opening the side walls of the trough 101 are extended upwardly as at 101^a and these extended portions are provided with a cover 103 and with a back plate 104.

Secured to and extending between the side walls 100' of the chute is a horizontal plate 105 positioned so that its upper surface substantially coincides with the plane of the upper edges of the trough, and attached to this plate 105 is an angle bracket having its vertical leg 106 of substantially the same shape as the cross section of and fitting within the trough.

The trough 101, at its forward or discharge end 101', passes between a pair of guide plates 107, extending upwardly from a chamber 108, from which chamber extends a delivery pipe or conduit 109 to the housing 81.

Adapted to reciprocate within the chamber 108 is a horizontal plunger or piston 110, having at its rear end an upstanding lug 111, adapted to engage a pin 112, which may be inserted in any one of a series of holes 113, formed in a pair of

flanges 114 depending from the bottom of the trough 101. The lug 111 is also adapted to engage a cross wall 115 at the forward end of the flanges 114, and in fact the lug 111 may be said to play between the pin 112 and the wall 115. The plunger or piston 110 is held in proper position by means of a pair of auxiliary plungers 110^a disposed one at each side of the piston and rigidly secured to a bracket 110^c formed integral therewith. The plungers 110^a work in fixed guides 110^b and thus maintain the piston at all times in axial alignment.

Also formed integral with the bracket 110^c is a boss 110^d in which is set a pin 116 to the lower end of which is attached one end of a connecting rod 117, the other end of which is attached to a similar pin 118 set in a crank arm 119 secured to the upper end of a vertical shaft 120 journalled in a bearing bracket 121. Beneath this bracket, the shaft 120 is connected by a suitable universal joint with the upper end of a hollow shaft 120^a, which extends down to the rotating and discharging mechanism hereinafter described.

Referring to Fig. 5, I mount in an inclined position within the housing 81 just in front of the end of the delivery conduit 109, a pressure plate 109', pivoted at its upper end at 109^a and having secured to its lower edge adjustable weights 109^b, the number of which may be varied as desired.

The operation of the feeding mechanism above described will now be briefly set forth. The finely divided material is fed continuously into the upper end 100 of the feed chute, passing down into the trough 101, filling and overflowing the same, and then passing out of the bottom of the chute, from which point it may be returned by a suitable conveyor (not shown). Meanwhile, the piston 110 is being reciprocated by means of the connecting rod 117, and the lug 111 causes a similar reciprocation of the trough 101.

The wall 115 is so positioned that, at the extreme forward position of the piston 110, in which position its forward end enters the end of the conduit 109, the discharge end 101' of the trough 101 registers substantially with the forward edge of the cylinder 108. With the pin 112 in its extreme forward position, as shown in Fig. 15, the trough is retracted, when the piston moves back, into the position shown. Thus, the piston and trough reciprocate together except for a slight lost motion due to the space between the pin 112 and wall 115. Starting with the trough in the position shown in the drawings, the material entering the top 100 of the chute will fill and overflow the trough at a point immediately in front of the fixed angle bracket 106, this material entering the trough between the fixed plate 105 and the movable vertical plate 104. Upon forward movement of the trough from this position, more material falls in behind that which is already there and in front of the angle bracket 106. Upon backward movement of the trough, this material is pushed forward by the angle bracket 106, and at the same time the vertical wall or stripper plate 104 serves to level off the material in the trough so that the material is never heaped up in the trough at any point forward of the stripper plate 104. The trough is maintained level full, the cover plate 103 preventing any material entering the trough in advance of the stripper plate 104.

It was stated above that as the trough moved

rearwardly, the angle bracket 106 pushed the material forward in the trough. It would be more accurate to say that as the trough moves rearwardly, the angle bracket holds the material in the trough stationary while the trough travels back beneath this mass of material.

Upon successive reciprocations of the trough, additional quantities of material enter the rear portion thereof until the trough becomes full throughout its entire length in front of the bracket 106. After the trough has become full, it will be apparent that, upon the next return or rearward movement, a measured quantity of material is discharged from the forward end 101' of the trough into the cylinder 108. This measured quantity represents a mass of a section equal to the cross section of the trough and of a length equal to the stroke thereof.

With the pin 112 in the position shown in Fig. 15, the device is set for delivering the maximum quantity of material at each stroke, that is to say, a batch of material occupying a lineal distance in the trough equal to the full width of the chamber 108 is forced from the end of the trough and drops into the chamber. If it be desired to feed smaller batches or measured quantities of material, the pin 112 is placed in one of the other holes 113, further toward the rear. In this case, the trough 101 will be moved to the same extreme forward position, but, on its return stroke, will be moved only part way back, that is to say, the delivery end 101', instead of being retracted to the position shown in Fig. 15, will stop at some intermediate position in which it partly overhangs the open top of chamber 108. The volume of the batch of material delivered at each stroke is, of course, proportional to the length of the stroke of the trough or, in other words, to the longitudinal dimension of the mass of material which is ejected from the end of the trough upon its return stroke.

From the foregoing, it will be understood that the material is fed into and through the chute at a rate in excess of the maximum rate at which it is to be delivered into the retort, and that the reciprocating trough serves to intercept a portion of the stream of material passing through the chute and deliver such intercepted portion in the form of successive batches of predetermined volume in front of the piston 110. In this way, the difficulties heretofore experienced in the feeding of finely divided materials from filled hoppers is avoided on the one hand, and on the other hand, the danger of overfeeding material in front of the piston and thus producing abnormal stresses in the mechanism is eliminated. With my improved arrangement, the volume of material deposited in front of the piston is automatically limited.

Referring again to Fig. 5, the material forced by the piston 110 out of the cylinder 108 passes into and through the conduit 109, and finally accumulates against the weighted pressure plate 109'. When the space within the conduit and beneath the pressure plate becomes completely filled with material, the pressure of the piston causes the plate 109' to swing upwardly on its pivot at each stroke and permit a definite amount of material to pass and to be discharged through the opening 75^a and down the chute 80, it being understood that at each stroke of the piston the same amount of material is forced past the pressure plate 109' as is delivered by the trough 101 into the cylinder 108.

The purpose of the pressure plate, therefore, is

to maintain the delivery conduit 109 completely filled with a compact mass of material, so as to form a substantially tight seal to prevent the escape of gaseous products out through the feed mechanism.

Driving and discharge mechanism

At its lower end, the hollow shaft 120^a is connected by a suitable universal joint to the upper 10 end of a vertical shaft 122 journaled in bearings 123 carried by the top of a gear casing 125, and bearings 124 mounted within said casing, which casing is supported on the base plate 3. Between the bearings 123 and 124, there is rigidly secured to the shaft 122 a bevel gear 126 meshing with a similar gear (not shown) secured to a drive shaft 127 (Fig. 3) connected with variable speed reducing gearing 128, driven by a motor 128', the speed of the shaft 127 being regulated by means of a control 128a.

On the lower end of the shaft 122, below the bearing 124, is secured a pinion 129, which meshes with a gear 130, secured to a short vertical shaft 131, journaled in suitable bearings and carrying at its lower end gear 132. The gear 130 meshes with and drives the ring gear 12 secured to the rotating cylindrical shell of the retort, as above described, and the gear 132 meshes with a gear 133, secured to the upper end of a vertical shaft 134. This shaft is journaled in bearings formed in a short cylindrical casing having upper and lower parallel walls 136 and 140. Fitting snugly between these walls and within the cylindrical sides 138 of the casing is a discharge wheel comprising a hub 139, and a plurality of spokes 139^a radiating therefrom (Fig. 20), these spokes, in combination with the cylinder 138, forming closed cells.

At the side adjacent the retort, the top plate 136 has an opening 141 adapted to register successively with the cells between the spokes 139^a as the discharge wheel rotates, and on the opposite side of the casing, the bottom plate 140 is provided with a vertical discharge opening 141^a, with which the cells in the discharge wheel are likewise adapted to successively register (Fig. 4). The lower end of shaft 134 preferably is supported on the end of an adjustable bearing screw 134^a. By this means, the discharge wheel may be accurately positioned between the upper and lower plates 136 and 140, and prevented from dragging upon the lower plate.

Formed in the bottom plate 3 at a point directly above the opening 141 is a discharge opening 3^a, and a chute 142 is arranged to conduct the material from the opening 3^a and deliver it into the opening 141.

General operation

Power being supplied by the motor 128, the vertical shaft 122 and with it the hollow shaft 120^a and vertical shaft 120 is driven and through the gears 129 and 130 and ring gear 12 the cylindrical shell of the retort is rotated. This shell carries with it, in its rotation, not only the various conveyor elements which are connected to it by lugs or drag chains, but also the plate 90, cylinder 92, and scrapers 94 carried at the top of the apparatus. The stack of heating elements, and all other parts of the superstructure are, of course, stationary.

The material being fed into the housing 81, as above described, is discharged downwardly through the opening 75^a and chute 80, into the cells of the topmost conveyor element.

It will be noted that since the feed mechanism and the cylindrical shell rotating mechanism are geared together, they operate with a constant speed ratio, and by properly selecting this ratio, it is possible to so arrange the apparatus that a measured batch of material is delivered from the lower end of the chute 80 each time a cell of the conveyor element passes under the chute. In other words, successive measured batches of material are delivered into successive cells as the topmost conveyor element rotates.

As in my prior patent, above identified, the material falls, cascade fashion, from one heating element to another, passing through the openings or notches 38, which notches are offset from each other and arranged in the form of a spiral. It will be understood that the direction of rotation of the shell and conveyor elements is clockwise, as indicated by the arrow in Fig. 3 and Fig. 10, the successive notches in the heating elements being offset in the direction indicated in Fig. 10. In this way, the material deposited on one heating element makes fifteen-sixteenths of a complete revolution before being discharged through the notch onto the heating element next below. Thus, in Fig. 2, the notch 38 in the topmost heating element is displaced in a counter-clockwise direction one-sixteenth of a revolution or $22\frac{1}{2}^\circ$ from the chute 80 under the housing 81, at which point the material is deposited, and each successive notch, progressively down the series of heating elements, is displaced $22\frac{1}{2}^\circ$ in a counter-clockwise direction from the position shown at 38 in Fig. 2, until the notch 38 in the lowermost heating element, as shown in Fig. 4, is directly under the housing 81 (Fig. 2) where the material enters the retort.

The spent material discharged from the lowermost heating element passes through the opening 3a in the base plate and thence through the chute 142 into the discharge wheel 139, whence it is delivered from the discharge opening 141a. The discharge mechanism, above described, in which the material enters the cells at one side of the cylindrical casing and is discharged from the opposite side thereof, provides a gas tight seal to prevent the passage of gaseous products therethrough. It will be noted that the discharge mechanism is also geared to the shaft 122 so that it is always driven at a speed which bears a fixed ratio to the rotation of the main cylindrical shell and the operation of the feed mechanism. The capacity of the cells 139a in the discharge wheel is preferably somewhat greater than the volume of the maximum measured batches of material fed into the retort at the top.

Since measured batches of material of uniform volume are successively fed into the cells of the uppermost conveyor element, it will be seen that when these cells are filled (either partly or wholly full, depending upon the stroke of the feeding mechanism, as above explained) the material therein is in the form of a layer of uniform thickness, and the rotation of the conveyor elements causes this layer to slide along in contact with the upper surface of the heating elements. I have found that this method of subjecting finely divided material to indirect heat, namely, by confining it within cells having closed sides, or, in the form of a layer of uniform thickness, and causing this layer to slide progressively over the surface of a hot plate, is a very efficient one and possesses marked advantages.

Inasmuch as the rotating means, feeding means and discharging means are all geared together,

it is possible to vary the time during which the material is subjected to the action of heat without varying the thickness of the layer of material or making any other relative adjustments. This may be done simply by manipulating the control 128a of the variable speed drive 128, in order to vary its speed.

One of the chief practical difficulties in the processing of finely divided resinous wood and other materials of this nature is the tendency of such materials to cake or coke under the influence of heat, and adhere to the surfaces with which they are in contact. Thus, in continuous retorts of the type described herein, in which the material is intended to fall by gravity through the openings or notches in successive heating elements, it frequently happens that owing to caking or coking, the material clings to the side walls of the conveyor element and is not discharged therefrom by gravity when it passes over the openings in the heating elements. This results in interrupting the flow of material through the retort and jamming or choking of the apparatus.

One of the important features of the present invention is the provision of means for forcibly ejecting caked masses of material from the conveyor cells. This is the purpose of the arcuate ribs 40 having the lower inclined surfaces 40a, as shown in Figs. 6, 7 and 10. By reference to Fig. 10, it will be observed that these ribs are carried by the lower face of each heating element and overlying the notch or opening 38 of the heating element next below, the lowest point of the inclined surface of the ribs being immediately above such opening. It will further be observed by reference to Fig. 10 that the depth of the ribs increases progressively in the direction of rotation of the conveyor elements, as shown by the arrow, and the lowest point lies slightly above the plane of the upper surface of the conveyor element.

As long as the material remains as a layer of uniform thickness in the cells of the conveyor element, or as long as it does not project above the upper surface of such cells, the ribs 40 have no effect. If, however, the material should fail to fall out of any cell as it passes over the opening in the heating element, and this cell should travel around again and receive another charge of material on top of that already in the cell, so that the material is heaped up in the cell, as shown in Fig. 10, then when this mass of heaped up material is carried underneath the inclined surface of the ribs 40, such inclined surface will serve to force the material downward and eject it from the cell through the opening below, breaking up any caked masses and disengaging them from the side walls of the cell. Experiments have shown that no matter how badly the material may be caked in a cell, the device just described will serve to effectively break it loose and clear the cell for receiving the next charge.

My improved means for circulating a gaseous heating medium through the heating elements and means for controlling the temperature of the gaseous heating medium are especially important features of my improved apparatus. Referring to Figs. 3, 4, 5, 17, 18 and 19, it will be seen that the fan 61 is in series with the flue passages formed by the base of the apparatus and the plurality of heating elements supported thereby. It will thus be understood that hot gases from the furnace 56 are delivered into the radial duct 54, (Fig. 4) from which they pass

into the annular space within the base and thence upwardly through the supporting ring 20 into the interior of the lowermost heating element 27, and thence successively upward through the interiors of each heating element in turn. It will be observed that the position of the baffles 33 is such that the hot gases are caused to follow a radially zig-zag path, flowing outwardly over the bottom wall of the heating element and thence radially inward along the upper wall.

As shown in Fig. 5, the hot gases emerging from the uppermost heating element, and passing around the topmost baffle 33, flow downwardly through the central axial conduit formed by the cylindrical sections 42, and thence, as shown in Fig. 17, out through the axial pipe 45, radial duct 46, and discharge flue 62, to the fan 61 (Fig. 3) from which they are delivered back again through the pipe 58 (Figs. 3 and 18), into the conduit 55, thus making a complete circuit through the conduit system including the flue passages within the heating elements.

This arrangement of a complete circuit of flue passages in series with a circulating fan, but independent of the furnace, is one of the vital features of my improved retort, and it is important that the cross-sectional area of the flue passages composing the circuit be amply sufficient to permit the ready circulation of large volumes of gases through them.

As has already been described, the circuit of flue passages comprises an inlet duct or nozzle 57 (Fig. 4), and an outlet duct or discharge stack 60, branching therefrom. (Figs. 3 and 18). The amount of gas expelled by the fan 61 through the outlet duct 60, may, as above explained, be regulated by means of the damper 63. Each foot of gas expelled through outlet 60 under pressure is replaced by a similar amount drawn inward through duct 57, by the partial vacuum created at the intake of the fan, which incoming gas is derived from the combustion of fuel in the furnace 56.

If the damper 63, (Fig. 18) is set so that the outlet 60 is completely closed, then there is no inflow of gas through duct 57 and no inflow of air through the draft openings 56^b of the furnace and therefore no combustion of fuel within the furnace. Consequently there would be no additional heat being introduced into the mass of gas being circulated by the fan through the closed circuit of flue passages just described, including the heating elements. However, at all times that the fan 61 is in operation, a large volume of gas is being circulated through the heating elements and around the closed circuit of flue passages, exclusive of the furnace, as described, that is to say, the same gas, after passing up through the heating elements, is forced by the fan to recirculate therethrough again and again. Under these conditions, the temperature of the heating elements is relatively low.

When, however, the damper 63 is opened to a slight degree, as illustrated, for example, in Fig. 18, thus deflecting through the discharge outlet some of the gases being circulated by the fan, a certain amount of air will enter the furnace chamber through the draft openings 56^b, which air may support the combustion of a definite amount of fuel injected into the furnace through the burner 56^a. The gases resulting from the combustion of this definite amount of fuel must be enough in volume to compensate for the volume of gas being expelled by the fan through the discharge outlet 60. It will thus be seen that

each setting of the damper 63 requires such an adjustment of the burner 56^a as will result in the production of a corresponding volume of high temperature gases of combustion, which gases flow from the furnace through the nozzle 57 and mix with the stream of gases being circulated by the fan at high velocity through the heating elements as described.

With the damper 63 set in its lowermost position, there would be no recirculation of gases at all, as the entire volume passing through the fan would be drawn in through the draft openings 56^b of the furnace and expelled through the discharge stack 60. This would afford a maximum supply of air for the combustion of the maximum amount of fuel, thus producing the conditions for maximum temperature of the gases passing through the heating elements. Such maximum temperatures are usually undesirable and a major purpose of my improved method of limiting the combustion of fuel by the setting of the damper 63 is to guard against undesirably high temperatures.

In actual operation of the apparatus, a desirable maximum temperature for the circulating of hot gases at the point where they enter the lowermost heating element would be selected, a suitable pyrometer (not shown) being mounted at this point to indicate the temperature. This desired maximum temperature is then obtained by starting the circulating fan 61, adjusting the damper 63 so as to induce a flow of air through the draft openings 56^b, then adjusting the burner 56^a so as to obtain the efficient combustion of the fuel injected by it. Then the amount of fuel being burned may be increased or decreased by successive adjustments of the damper 63 and the burner 56^a until the desired maximum temperature of the circulating gases as indicated by the pyrometer is obtained and maintained. When equilibrium is reached, as indicated by a substantially constant reading of the pyrometer, it is obvious that the heat generated by the combustion of fuel is just sufficient to compensate for the heat being transmitted and lost through the walls of the heating elements and being discharged by the fan through the stack 60.

Thus the apparatus may be set for perfect combustion of the fuel. This insures production of a non-oxidizing circulating medium, and it will be noted that there is no dilution of the circulating gases with air, at any time.

It remains to describe the path of the vapors and gaseous products given off from the material being processed. It is preferable that the heating elements be thoroughly heated prior to the introduction of the material being processed, and that the mass and temperature of the heating gases being circulated through the heating elements be such that the desired temperature of the heating elements is maintained after the processing of the material is started. It has been found that a highly satisfactory temperature range for the circulating heating gases is that they should enter the bottom heating element at approximately 1,300 degrees F., and return to the circulating fan at approximately 900 degrees Fahrenheit. This temperature range keeps the topmost heating element at substantially the temperature at which the carbonization of wood progresses as an exothermic reaction.

As above pointed out, the finely divided wood or other material is fed in at the top of the retort in successive measured amounts to form a layer within the rotating topmost conveyor element,

which moves the layer, without substantial agitation, of the particles composing it, in sliding contact with the top surface of the heating element. Each conveyor element delivers the material carried by it, in cascade fashion, to the next lower conveyor element and thus the stream of material being processed is successively moved over the surfaces of the entire number of heating elements; each succeeding lower element being progressively of higher temperature. In cascading from one heating element to the next lower element the particles composing each layer of the material being processed are substantially rearranged. The porous layers of finely divided particles are very poor conductors of heat and only those particles in direct contact with the top surface of the heating element are subjected to a rapid rise in temperature. These contacting particles, however, very quickly approach the temperature of the heating element. It has already been observed that it is preferable to have all the heating elements maintained at temperatures in excess of the temperature required to produce the exothermic breakdown of the material, viz., approximately 850 degrees F. in the case of wood. The particles of each layer contacting the heating element, therefore, are very quickly carbonized and the resultant vapor and gaseous products move vertically away from the surface of the heating element and flow through the superimposed porous layer of cooler particles, and rapidly transfer their heat, in the case of vapors, by condensation. With each transfer of the porous layers of material from one heating element to the next lower heating element, fresh particles of wood or other material are brought in contact with the surface of the heating element and in turn are rapidly carbonized with a continued movement of the gaseous and vapor products upward through the cooler material with consequent condensation and transfer of heat to the cooler materials. As the temperature of the entire porous layer of material is rapidly increased by this dual method of heating, reevaporation of the liquids, resulting from the previous condensation of vapors, takes place. The dual method of heating, above referred to, includes heating by conduction from the hot surface of the heating elements, and heating by the exothermic reaction brought about by the breakdown of the material particles in contact with the heating element, the exothermic heat being stored in the vapor and gaseous products. In the above mentioned reevaporation, the lower boiling liquids are first vaporized and the higher boiling liquids remain mixed with the particles composing the layer. There is thus an accumulation of high boiling liquids in the layer as it rapidly approaches the critical temperature at which the remainder of wood particles contained in it break down with a further liberation of exothermic heat. The presence of the accumulation of high boiling liquids in the layer serves to absorb this exothermic heat as heat of vaporization, thus serving to quickly cool the vapor products of carbonization to a degree that materially inhibits cracking.

The vapors and gases which escape from any layer of material flow to the opening 38 in the heating element immediately above the layer of material and mingle with the stream of gases and vapors from other layers of material flowing upward through the broken spiral passage way formed by the said openings in the heating elements, and moving through zones of progressive-

ly decreasing temperature, thus further inhibiting the cracking of the vapor products.

The greater part of the gaseous products emerge through the opening 38 in the topmost heating element, this opening being in the position shown in dotted lines in Fig. 2. The products then mostly flow around the annular chamber between the cylinders 78 and 79, in a counterclockwise direction, as indicated by the dotted arrow in Fig. 2, and pass into the opening 88 at the diametrically opposite side of the retort.

From the opening 88, the gaseous products pass upwardly into the cylindrical chamber 82, and are then discharged radially therefrom through the conduit 96.

Thus the gaseous products flowing through the superstructure, as above described, are caused to sharply change their direction at a number of points. This sudden change in direction tends to cause any solid particles entrained or carried along with the gases to be deposited either in the trough 87 or on the walls of the cylindrical chamber 82, and, as above described, such deposited material is continuously removed by the rotating scraper blades and returned to the topmost conveyor element.

My process, which has been described in connection with the movement of finely divided woods and other similar materials, over a succession of hot heat-conducting surfaces in the order of ascending temperature, opens a broadly interesting field of modifying vapor products of destructive distillation by contacting them with acid or other vapors derived from materials added to the finely divided wood prior to its introduction into my apparatus, and by contacting them with active gases such as chlorine or sulphur dioxide which may be admitted in controlled amounts at the base of the apparatus. Various catalytic agents may also be added to the finely divided materials being processed and the aggregate layer of material subjected to the action of heat delivered by direct contact of the material with the heat conducting surface.

While in the claims I have used the word "retort" in defining the invention, it will, of course, be understood that this term is intended to be broad enough to include apparatus for drying or otherwise processing material, as well as for subjecting the same to destructive distillation.

Many of the features set forth in the preamble and illustrated and described in detail in the specification and drawings are not claimed herein but form the subject matter of my copending divisional applications Serial No. 427,661, filed January 21, 1942, and Serial No. 470,471, filed December 29, 1942.

What I claim is:

1. The combination with a retort, of a conduit, one end of which is connected therewith at one point, a source of hot gases separate from said retort delivering into the other end of said conduit, a flue connected with said retort at another point, a pipe communicating with said flue and tapping said conduit at a point between its ends, means independent of said source for causing a forced circulation of gases through said conduit, retort, flue, and pipe, and means for deflecting and ejecting from said pipe at a pressure above atmospheric a portion of the gases flowing therethrough.

2. The combination with a retort, of a conduit, one end of which is connected therewith at one point, a source of hot gases separate from said retort delivering into the other end of said con-

duit, a flue connected with said retort at another point, a pipe communicating with said flue and tapping said conduit at a point between its ends, means for causing a forced circulation of gases through said conduit, retort, flue, and pipe, and adjustable means for ejecting and discharging from said pipe any desired portion of the gases flowing therethrough.

3. The combination with a retort comprising a vertical series of superposed hollow annular heating elements, and means for causing fluent material to be treated to travel downwardly over said elements, of a source of hot gases, means for causing gases to flow from said source into the lowermost of said elements, thence upwardly through the series, and thence downwardly through the center thereof, a discharge flue into which the gases pass from the bottom of the retort, means independent of said source for recirculating through the heating elements a portion of the gases passing into said flue, and means for varying as desired the portion thus recirculated.

4. Apparatus for heat treating materials comprising a retort containing a heating element having a wall, a conduit system forming a closed circuit, including said element, means for causing the material to be treated to travel through said retort over one surface of said wall, means for generating hot gases, a power driven fan in said circuit for producing a forced circulation of said gases therethrough and over the other surface of said wall, said conduit system having a vent at the discharge side of said fan, and an adjustable damper mounted within said conduit system adjacent said vent for splitting the stream of gases delivered by said fan without restricting the same and deflecting and ejecting from said vent any desired portion thereof.

5. Apparatus for heat treating fluent materials comprising a hollow heating element having a wall, means for causing fluent solid or liquid material to be heated to travel over the outer surface of said wall, a generator of hot gases independent of said material open at one side directly to atmosphere and communicating at the other side with the interior of said element, a suction fan operating at substantially constant capacity, a discharge stack and means operated solely by and including said fan for drawing air into and through said generator at a pressure no greater than atmospheric, and causing the resulting hot gases to flow over the inner surface of said wall and out of said stack.

6. Apparatus for heat treating fluent materials comprising a hollow heating element having a wall, a generator of hot gases open at one side directly to atmosphere, means for causing the material to be heated to travel over a path including one surface of said wall but excluding said generator, a conduit system forming a complete circuit including said element, said generator communicating at its other side with said conduit system but being excluded from said circuit, a suction fan in said conduit system, and means operated solely by and including said fan, for drawing air into and through said generator at no more than atmospheric pressure, and for causing the resulting hot gases to flow around said circuit and over the inner surface of said wall, all of the gases flowing over said wall passing through said fan.

7. Apparatus for heat treating fluent materials comprising a hollow heating element having a wall, means for causing the material to be heated to travel over the outer surface of said wall, a generator of hot gases open at one side directly to atmosphere, a conduit system forming a complete circuit, including said element, said generator communicating at its other side with said conduit system but being excluded from said circuit, a suction fan, means whereby said fan causes gases from said generator to circulate continuously through said circuit and over the inner surface of said wall, an outlet stack at the pressure side of said fan, adjustable means adjacent said stack for deflecting from said circuit and discharging into said stack any desired portion of the gases circulating, and means operated solely by and including said fan for creating in said generator a pressure less than atmospheric and thus drawing into the same such amounts of air as are required to form sufficient hot gases to replace those discharged.

8. The combination with a retort, a source of hot gases communicating therewith, and a conduit system forming a complete circuit including said retort, said source communicating with said circuit system but being excluded from said circuit, of a discharge stack tapping said conduit system, a suction fan in said conduit system at a point between said retort and stack, said fan having its inlet side connected with said retort, in such manner that all gases coming from said retort pass through said fan, an adjustable damper between the outlet of said fan and said stack and means whereby the volume of gases passing through said fan and retort remain constant for any given velocity of the fan, regardless of the setting of said damper.

9. The combination with a retort, a source of hot gases communicating therewith, and a conduit system forming a complete circuit including said retort, said source communicating with said circuit system but being excluded from said circuit, a suction fan in said conduit system for drawing hot gases from said source into said circuit and for causing them to re-circulate continuously therethrough, all of said gases passing through said fan, a discharge stack tapping said conduit system at the delivery side of said fan, and an adjustable damper for deflecting out of said closed circuit and into said stack any desired portion of said gases.

10. The combination with a retort comprising a vertical stationary structure having annular walls, means for feeding into the top of said structure material to be heated, means for causing said material to travel downwardly by gravity over one surface of said annular walls, a source of hot gases, a power driven fan for causing gases to flow by suction from said source into the lower end of said structure, thence upwardly over the other surface of said annular walls in a direction opposite to that in which the material is moving, and thence downwardly into a discharge flue, means including said fan for re-circulating over the above mentioned path, independently of said source, any desired portion of the gases passing into said flue, and an outlet stack at the pressure side of said fan into which that portion of the gases not re-circulated is forcibly ejected.

CERTIFICATE OF CORRECTION.

Patent No. 2,310,215.

February 9, 1943.

McGARVEY CLINE.

It is hereby certified that error appears in the printed specification of the above numbered patent requiring correction as follows: Page 2, second column, line 62, for "in" before "an" read --is--; page 3, first column, line 17, after "lugs" insert --every--; line 24, for "notch 38" read --notch 38--; page 10, first column, line 6, for "ejecting and discharging" read --deflecting and ejecting--; and second column, lines 27 and 43, for "circuit" before "system" read --conduit--; line 66, for "independently" read --independently--; and that the said Letters Patent should be read with this correction therein that the same may conform to the record of the case in the Patent Office.

Signed and sealed this 16th day of May, A. D. 1944.

Leslie Frazer

(Seal)

Acting Commissioner of Patents.
